UNITED STATES PATENT OFFICE.

RALPH D. MERSHON, OF NEW YORK, N. Y.

CUTTING SHEET METAL.

1,332,445.

Specification of Letters Patent.

Patented Mar. 2, 1920.

Application filed April 3, 1917, Serial No. 159,394. Renewed July 18, 1919. Serial No. 311,904.

To all whom it may concern:

Be it known that I, RALPH D. MERSHON, a citizen of the United States, residing at New York, county and State of New York, have 5 invented certain new and useful Improvements in Cutting Sheet Metal, of which the following is a full, clear, and exact description.

In my copending application Ser. No. 10 159,146, filed April 2nd, 1917, I have described an electrode, for use in electrolytic condensers and other electrolytic apparatus, composed of a crimped or corrugated strip of thin sheet metal carried by a metal 15 supporting frame. For the purpose of securely holding the sheet metal plate the upper and lower edges thereof are grooved across the folds or corrugations, to receive the edges of the upper and lower members of the supporting frame. To make this groove by 20 prior methods without mashing the folds or otherwise distorting the plate is a difficult operation, and it is accordingly the chief object of my present invention to provide a 25 simple method by which the groove can be quickly and easily cut without the slightest injury to the plate. To this and other ends the invention consists in the novel features hereinafter described.

30 In the accompanying drawing, Figure 1 is a side view of a portion of an electrode having a crimped plate provided with a groove in its upper edge to receive the upper member of the supporting frame. Fig. 2 is a detail perspective view showing the upper-frame-member in the groove. Fig. 3 is also a detail perspective view, showing the grooved upper edge of the crimped plate. Fig. 4 is a detail sectional view showing 35 the edge of the crimped plate inserted in a trough-shaped mold, for casting on said edge a block of fusible material. Fig. 5 is a detail perspective view showing the edge of the crimped plate and a block of fusible 40 material thereon, filling the spaces between the folds. Fig. 6 is a similar view, showing the groove and a hole cut through the fusible block and the folds embedded therein.

The "plate" 10 is composed of thin sheet 50 metal and is folded or crimped so that it may be used in a vessel or cell (not shown) of convenient size. To give it mechanical strength it is mounted in a suitable supporting frame, of which the upper cross member 55 is shown at 11 and one side member at 12. The lower edge of the said upper member

extends into a groove 13 in the adjacent edge of the plate 10, which groove is simply a series of alined notches cut in the upper ends of the folds or crimps.

In cutting the groove by my present method the individual folds are supported on each side by fusible material which fills the space between adjacent folds. This holds the folds apart at the proper distance. 65 The groove is cut, for example by sawing, through the folds and the interposed material, the latter serving as a support for the sheet metal and so preventing mashing of the folds and formation of heavy burs at 70 the edges of the cut. Preferably the desired support is provided by casting a block of the fusible material on the edge-portion of the plate, the material or substance used being one that has a lower melting point than 75 the metal of the plate. Among the various materials that can be used I may mention lead, zinc, or tin, or other metal or an alloy of two or more of the same; or non-metallic materials and compositions, for example sulfur, shellac, rosin, etc., with or without admixture with other substances, fusible or non-fusible. Preferably I use a mixture of sulfur and graphite, especially with aluminum plates. In this composition the 80 graphite makes the sawing easier, partly because it permits less sulfur to be used, and partly because of its lubricating effect.

The supporting block can be conveniently cast upon the crimped plate in the following manner.

A mold is prepared in the form of a trough 14 (preferably in two or more separable parts) slightly deeper than the groove that is to be cut, and the molten material is 95 poured into the mold. The edge of the plate is then inserted into the molten material to a point well above the point where the bottom of the groove is to be. The edge of the plate,—composed of the end portions of the 100 folds,—is thus embedded in a solid block 15, Fig. 5. A groove 16, Fig. 6, can now be cut across the folds, as by sawing or milling, or a hole 17 can be bored through the folds, without distorting the same in the slightest 105 degree and even without leaving an appreciable bur on the edges of the thin sheet metal. The block of fusible material is then melted off, leaving the crimped plate as it was originally except for the presence 110 of the groove 13 or hole 17, or both.

The crimped plate is then mounted in its

supporting frame, and is electrically connected to the latter in any convenient and suitable manner, as by welding one or more strips 17, cut from the plate, to the upper 5 member 11 of the supporting frame.

It is to be understood that the invention is not limited to the specific details of procedure herein described; nor is it limited to use in the manufacture of electrodes but can 10 be used for cutting sheet metal for numerous other purposes. It is also to be understood that the method of making the cut, whether by boring, drilling, milling, sawing, or the like, is immaterial.

15 I claim:—

1. The method of cutting a clean aperture in sheet metal without distortion or material burring, comprising casting on the sheet metal about the place where the cut is 20 to be made a block or body of material having a lower melting point to support the sheet metal, cutting the desired aperture through the cast material and the sheet metal, and melting off the remaining cast 25 material.

2. The method of cutting an aperture through a plurality of spaced layers of

sheet metal, comprising casting between such layers at the point where the aperture is to be made a block or body of material 30 having a lower melting point to support the sheet metal whereby the separation of the successive layers thereof will be maintained, cutting the desired aperture through the cast material and the spaced layers of sheet 35 metal, and melting out the remaining cast material.

3. The method of cutting an aperture through the spaced folds of a folded or crimped sheet metal plate of the kind described, comprising casting upon the plate and into the folds thereof at the point where the aperture is to be made a block or body of material having a lower melting point to maintain the separation of the folds and 45 prevent distortion thereof, cutting the aperture through the cast material and the successive spaced folds of the sheet metal, and then melting out the remaining portion of 50 the cast body.

In testimony whereof I hereunto affix my signature.

RALPH D. MERSHON.
